EVAPORATING DISSEMINATOR

George J. Eisner, Phoenix, Ariz.

Application April 11, 1944, Serial No. 530,543

1 Claim. (Cl. 21—120)

This invention concerns evaporating disseminators, of the type adapted to vaporize volatile materials, such as insecticides, deodorants, and the like, with heat obtained from an independent source on which the device is placed. It has for its objects,

First, to provide an evaporating vapor disseminator which can be made of metal, plastics or other heat resisting material which can be conveniently attached to an incandescent lamp globe, or otherwise placed on other heat producing devices;

Second, the provision of a device as above mentioned which will hold substances to be evaporated without spilling, when the device is placed at any desired angle other than horizontal;

Third, the provision of a device, as above mentioned, composed of a minimum of parts, arranged so as to be cheaply fabricated, and adapted to maximum surface contact with the heating surface of a conventional electric lamp globe, and provided with semi-resilient retaining members to hold the device on various shaped lamp bulbs or globes, or on such other heating devices as is desired.

Other objects will appear hereinafter.

I attain the foregoing objects by means of the devices and construction shown in the accompanying drawing, in which—

Figure 1, is a side elevational view of the device in operative position on an incandescent lamp globe;

Figure 2 with the filling cap removed;

Figure 3, a vertical section taken on line 3—3 of Figure 2;

Figure 4, a side elevational view of a modified form of the device when made of plastic material, and;

Figure 5, an elevation of the filling plug.

Similar numerals refer to similar parts in the several views.

The essence container or vessel 2 of the device is composed of two main parts, an upper cup shaped part 3, in inverted position, and a lower bottom part 4 forming a closure for the opening at the bottom of the upper part. The vessel preferably has the shape of the frustum of a cone. When made of metal the two parts are stamped and die pressed to shape. When made of plastic they are molded. The top part 3 has a hole 5 formed in the center of its upper face provided with notches 6, depending tab stops 7, and inwardly extending partial screw tightening lips 8. This construction accommo-

dates closure plug 9 which has two lugs 10 adapted to insertion through slots 6 and arranged to engage said screw tightening lips 8.

The bottom closure part 4 has its central portion shaped to form a concave bottom conforming to the outer surface of the conventional incandescent lamp bulb or globe of average size. This concave surface is shaped to afford the best contact with the globe surface for heat transfer; it also operates to converge heat rays toward the interior of the vessel. Three holding fingers 12 are formed integral with the central portion. These fingers are equally spaced and normally shaped to conform generally to the surface of an average sized lamp globe, and as narrow as is consistent with the material used to furnish adequate resilient support and at the same time not diminish light given off from the lamp globe. To add stiffness to these fingers a head 14 is formed to extend down their middle substantially through their length. They are sufficiently springlike to resiliently hold the device on a globe. But yieldable enough to be flexed without breaking and may thus be bent to conform to larger or similar lamp globes, to form hooks, or to otherwise conform to various heating surfaces. Thus they may be termed semi-resilient. The lower ends of these fingers are bent outward to form feet 15. These form supports when the device is placed on a flat surface or the like. A number of holes 18 are drilled at equal intervals around the upper rim or periphery of the upper part of the vessel 1, to form vents through which vapors generated in the vessel may escape. Part 3 and part 4 are pressed together and soldered or cemented along seam 16, that is, the lower rim of part 3 is joined to the perimeter of the circular central portion of part 4. The domed closure or vessel thus formed is loosely filled with fibrous absorbent material 18 such as asbestos wool, or the like.

The modified form shown in Figure 4, is made of heat resistant plastic. The upper and lower parts are molded to have approximately the same shape as the metal parts composing the form shown in Figures 1, 2 and 3. The seam 16 between these parts may be closed by plastic cement, or a threaded joint may be provided. In this form the fingers 22 are made thicker, and to afford sufficient stiffness and resiliency, a metal wire 23 is imbedded in their interior and extends substantially throughout their length. In use the device is placed over a lamp bulb 19 as shown in Figure 1. The vessel 2 is supplied

with liquid material to be evaporated through hole 5 so far as it can be absorbed by the fibrous material 18. The plug 7 is placed in the filling hole, and the lamp lighted. As the liquid evaporates its vapors issue through vent holes 13. When desired the device may be placed on a flat surface, such as the top of a stove, radiator or register. Feet 15 afford support for this use. Liquids adapted to form moth repellent vapors, or deodorizing gases may thus be quickly evaporated. After evaporation these vapors are efficiently disseminated by the rising and convecting air currents associated with the heating element.

Having now fully described my invention and explained its use, I wish to be bound only by the following claim.

I claim:

An evaporator for volatile essence, and the like, composed of a vessel having the general 20 shape of a frustum of a cone and having a con-

cave bottom provided with a plurality of semi-resilient retaining fingers depending therefrom normally curved to conform to the surface of an electric lamp globe and having feet at their lower ends, a filling hole in the top of said vessel, and a removable plug therefor, a plurality of vent holes spaced around the upper rim of said vessel, and fibrous absorbent material filling the interior thereof; said vessel being composed of an upper part and a lower part; said upper part being cup shaped and joined in inverted position to said lower part, and said lower part having its central portion formed and shaped to provide a concave bottom closure for said upper part together with integral strips depending from said central portion forming said retaining fingers, said upper and lower part being joined in fluid tight relation.

GEORGE J. BISNER.
